Primary Examiner—Ted Shooman*Assistant Examiner*—C. Tuttle*Attorney, Agent, or Firm*—Ingrid McTaggart[57]*CLAIM

I claim the ornamental design for a lotion dispenser, as shown and described.

DESCRIPTION

FIG. 1 is an isometric view of the lotion dispenser, showing my new design;

FIG. 2 is a top plan view thereof;

FIG. 3 is a front elevational view thereof, the rear elevational view being a mirror image thereof;

FIG. 4 is a left side elevational view thereof, the right side elevational view being a mirror image thereof;

FIG. 5 is a bottom plan view thereof;

FIG. 6 is an isometric view of another embodiment of the lotion dispenser, showing my new design;

FIG. 7 is a top plan view thereof;

FIG. 8 is a front elevational view thereof, the rear elevational view being a mirror image thereof;

FIG. 9 is a left side elevational view thereof, the right side elevational view being a mirror image thereof; and,

FIG. 10 is a bottom plan view thereof.
